UNITED STATES PATENT OFFICE.

JOSEPH JORDAN PRITCHETT, OF MASON CITY, ILLINOIS.

DESIGN FOR A HOPPLE.

SPECIFICATION forming part of Design No. 33,052, dated August 7, 1900.

Application filed June 12, 1900. Serial No. 20,077. Term of patent 7 years.

To all whom it may concern:

Be it known that I, JOSEPH JORDAN PRITCHETT, a citizen of the United States, and a resident of Mason City, in the county of Mason and State of Illinois, have invented and produced a new and original Design for a Hopple, of which the following is a specification, reference being had to the accompanying drawings, forming a part thereof, in which—

Figure 1 is a perspective view of a hopple constructed in accordance with my design. Fig. 2 is a side elevation of the same, and Fig. 3 is a transverse section taken on the line 3 3 of Fig. 2.

The leading feature of the design consists of the body A, U-shaped in cross-section and having the downwardly and inwardly inclined longitudinal edges B, the ribs E along the longitudinal edges, the ribs D at the top and

bottom edges, and the inclined ribless corners F, said corners separating the longitudinal ribs from the upper and lower ribs.

A minor feature of the design consists of the panel C on the inner surface of the body, 25 said panel conforming to the contour of the said surface and extending lengthwise of the body.

Having thus described my invention, I claim as new and desire to secure by Letters 30 Patent—

The design for a hopple, herein shown and described.

In testimony whereof I have signed my name to this specification in the presence of 35 two subscribing witnesses.

JOSEPH JORDAN PRITCHETT.
